CONTACT DEVICE

Ragnar Holm, Berlin-Siemensstadt, Herbert Wüsteney, Berlin-Wilmersdorf, and Fritz Hennig, Berlin-Siemensstadt, Germany, assignors to "Fides Gesellschaft für die Verwaltung und Verwertung von gewerblichen Schutzrechten mit beschränkter Haftung," Berlin, Germany, a corporation of Germany

Application December 16, 1939, Serial No. 309,694
In Germany November 12, 1938

6 Claims. (Cl. 200—165)

This invention relates to a method of preventing the formation of protuberances on contacts caused by the wandering of the material.

When actuating electric contacts, particularly in direct-current circuits, the current causes a wandering of the contact material even if no arcs occur, and this may lead to a formation of protuberances and craters at the contact surfaces. Such deformations entail an improper engagement of the coating contacts, especially in the case of relays and other control contactors, and are a potential source of short circuits so that the contacts are short-lived and require continuous attention.

It is an object of the invention to prevent such disturbances caused by the above-mentioned wandering of contact material under arcless current conditions.

According to the invention the formation of protuberances is prevented by the fact that the wandering material which, for instance, has the form of dust or vapor is removed by an additional force from the zone of the corresponding point of contact. As an auxiliary force, centrifugal force is preferably utilized, for instance, so as to fling the wandering metal from the point of contact. Also the force of a magnet in the case of contacts consisting of magnetic metal, or the force of a current of air may be employed as an auxiliary force. In this case these means differ, of course, from the magnets or currents of air employed in known apparatus for extinguishing arcs.

In the accompanying drawing the invention is shown in diagrammatic form as applied to a relay. Fig. 1 shows a cited elevation of a relay in which a centrifugal force is used for preventing the occurrence of protuberances in accordance with the present invention. Fig. 2 shows schematically another relay wherein an air current serves for the same purpose.

The relay shown in Fig. 1 is constructed as follows:

To a shaft 1 is secured a disc 2 supporting an electromagnet 3. The armature of the magnet is pivotally mounted on a pin 4 arranged perpendicularly to the shaft 1. The armature 5 brings the contact 7 into engagement with the contact 8 against the force of a spring 6. The gap between the contacts may be adjusted by means of a set screw 9. The supply of energy to the contacts and magnet coil is effected with the aid of slip rings 10 by means of brushes 22. The slip rings are connected with the winding of magnet 3 and with contacts 7 and 8 as sche-

matically indicated by broken lines. 23 designates a motor for rotating shaft 1 and the device mounted thereon. It is assumed that a circuit in which a direct current of relatively great intensity flows is frequently closed and opened, for instance, for control purposes, by means of the contacts 7, 8, and that the relay contacts operate under current conditions not causing arc discharges. In this case the wandering of the material between the contact members is rendered ineffective by the action of the centrifugal force occurring when the shaft 1 rotates, which force causes the wandering particles to be flung away from the gap between the contacts in a direction towards the housing 11. The particles need not be completely removed from the gap, for it is sufficient that they are caused to move from the point just in contact to other points of the contact surface. In this manner the formation of craters and protuberances is prevented.

The relay shown in Fig. 2 has a stationary contact 17 and a movable contact 18, both non-rotatable. The armature 21, journaled at 14 and acted upon by a spring 16, carries the movable contact 18 and is controlled by a magnet 13. The nozzle 20 of an air blower is arranged so that the air current issuing therefrom in the direction of the arrow passes between the contact surfaces and removes the particles or gaseous substances apt to cause protuberances.

What is claimed is:

1. A contact device having a pair of coating contacts operating under arcless conditions, said pair of contacts being rotatable as a whole while its individual contacts are non-rotating relatively to each other, drive means for rotating said contact pair in a direction of rotation substantially in parallel to the contact surfaces of said contacts to effect a sweeping force on said surfaces, and control means for reciprocating said contacts relatively to each other between contact opening and closing positions, said drive means being operative simultaneously with yet independently of the operation of said control means.

2. A contact device for controlling electric circuits, comprising a set of contacts coating with each other under arcless current conditions, drive means for rotating said set of contacts in a direction of rotation substantially in parallel to the effective contact surfaces of said contacts, said contacts being arranged eccentrically relatively to said drive means so as to have said surfaces entirely removed from the axis of rotation for effecting a sweeping centrifugal force on all

points of said surfaces, and control means for moving said contacts of said set relatively to each other to open and close the circuit to be controlled, said drive means being operative simultaneously with said control means yet independently of the latter's control movements.

3. A contact device for controlling electric circuits having in combination, a supporting structure, a contact stationarily mounted on said structure, a movable member journaled on said structure, a movable contact on said member arranged to coact with said first contact, control means also disposed on said structure for causing said member to move its contact between circuit opening and closing positions, drive means comprising a rotary shaft connected with said structure and extending substantially perpendicularly to the surfaces of said contacts for producing a centrifugal force along said surfaces when in operation, and means for supplying energizing current to said control means during the operation of said drive means.

4. In combination, a contact device having coacting contacts non-rotatable relatively to each other yet relatively movable in the closing and opening direction, circuit means for supplying to said contacts a current below arcing conditions, means for producing an auxiliary force not affecting the contact movement of said contacts and substantially in the direction of the coacting

contact surfaces to prevent the formation of protuberances thereon, and control means for moving said contacts relatively to each other to switch said current during the operation of said force-producing means.

5. In combination, a relay type contact device having coacting contacts movable relatively to each other substantially only in the contact opening and closing direction, circuit means for passing through said contacts, when closed, a current below arcing conditions, mechanical control means for actuating said contacts to close and interrupt said current, and mechanical means for producing a sweeping force along the effective surfaces of said contacts and not affecting the operation of said control means and the movement of said contacts.

6. In combination, a contact device having coacting contacts non-rotatable relatively to each other yet relatively movable in the closing and opening direction, circuit means for supplying to said contacts a current below arcing conditions, blowing means for producing an air current directed so as to blow over the contact surfaces, and control means for actuating said contacts to switch said arcless current during the operation of said blowing means.
